RALPH S. RHOADS, OF ST. LOUIS, MISSOURI, ASSIGNOR TO EVENS AND HOWARD FIRE
BRICK COMPANY, OF ST. LOUIS, MISSOURI, A CORPORATION OF MISSOURI.

TILE.

1,145,214.

Specification of Letters Patent.

Patented July 6, 1915.

Application filed September 29, 1913. Serial No. 792,424.

To all whom it may concern:

Be it known that I, RALPH S. RHOADS, a citizen of the United States, residing at the city of St. Louis, State of Missouri, have 5 invented a certain new and useful Improvement in Tiles, of which the following is a full, clear, and exact description, such as will enable others skilled in the art to which it appertains to make and use the same, reference being had to the accompanying drawings, forming part of this specification, in which—

Figure 1 is a perspective view of my improved tile. Fig. 2 is an end elevational view showing two tiles assembled. Fig. 3 is a longitudinal sectional view showing a joint between the ends of two tiles.

This invention relates to a new improvement in tiles employed in the construction 20 of sewers, chimneys, silos, etc., and while the tiles or blocks are shown as having concavo-convex faces, it is obvious that they could have flat faces for use in the construction of straight, instead of curved walls.

25 The object of my present invention is to construct a tile of the character described whereby the mortar or cement employed to form the end joints will be confined and prevented from flowing back into the hollow spaces in the tile, and to this end I propose to provide a tile, the inner wall of which projects at one end, and there being a recess or rabbet provided in the face of the inner wall at the opposite end, which recess or rabbet is adapted to receive the projecting portion of the inner wall of an adjacent tile.

In the drawings, 1 indicates the inner wall of the tile, and 2 the outer wall.

40 3 and 4 are the side walls, the former having an undercut longitudinally disposed rib, 3^a, while the latter is provided with a longitudinal dove-tail groove 4^a, into which the rib 3^a fits in the formation of the side joint.

45 The inner wall 1 extends a short distance beyond the body of the tile at one end as designated by 1^a, while the opposite end of the inner wall terminates a short distance from the vertical plane occupied by the 50 outer wall 2 and side walls 3 and 4. A comparatively short wall section 1^c extends from the inset end of the inner wall 1 to the ver-

tical plane occupied by the ends of the walls 2, 3, and 4, which wall section 1^c is depressed or inset with respect to the plane occupied by the inner wall 1, and thus an abrupt shoulder 1^b is formed between said inner wall 1 and the short inset wall section 1^c. This short wall section 1^c is practically a continuation of the inner wall 1 and thus 60 such construction not only reinforces and strengthens this end of the tile, but it provides a transversely disposed rabbet or recess which when the two tiles are properly assembled or placed end to end receives the 65 projecting end of the inner wall of an adjacent tile and the mortar or cement used in joining said tiles. The abrupt shoulder at the inner end of the rabbet not only prevents the mortar or cement from flowing 70 backward into the hollow space within the tile, but the face of said abrupt shoulder forms a bonding surface for the cement or mortar which surface together with the face of the inset wall section 1^c provides ample 75 bonding surface between the end of the tile in which the rabbet is formed and the projecting end 1^a of the next adjacent tile. Thus, the inset wall section 1^c provides a bonding surface for the mortar or cement, 80 combines with the shoulder between said wall section and the inner wall of the tile to prevent the mortar from flowing into said tile, and further materially strengthens the 85 end of the tile which is provided with the recess or rabbet.

What I claim is:

A transversely curved hollow tile comprising an outer wall, a pair of side walls, an inner wall, one end of which is extended 90 a short distance at one end of the tile and the opposite end terminating a short distance from the corresponding ends of the outer and side walls, a short wall section 95 extending from the inset end of the inner wall to the corresponding ends of the side walls, thereby forming a transversely disposed recess or rabbet constituting a closed mortar pocket having an abrupt shoulder at its inner end, said rabbet being approximately equal in length and substantially twice the depth of the extended end of the inner wall at the opposite end of the tile so as to receive said extended end and a sub-

stantial body of mortar when a pair of the tiles are united, there being a longitudinally extending under-cut groove formed in the outer face of one of the side walls of the tile, and a dove-tailed rib formed on the outer face of the other side wall.

In testimony whereof I hereunto affix my

signature in the presence of two witnesses,
this 25th day of September, 1913.

RALPH S. RHOADS.
